HAIR CURLER

Rudolf Krasberg, Chicago, Ill.

Application April 20, 1944, Serial No. 531,876

8 Claims. (Cl. 132—34)

1

The present invention relates to hair curlers and more particularly to an improved hair curler which is simple and economical to manufacture and which is easily operated by the user.

The present invention relates to hair curlers of the type comprising a bar on which a curl may be wound.

Preferably the curl bar is hollow and may be perforated, and a suitable gripper may be employed whereby one end of the curl may be secured to the bar. In order to prevent the curl from unwinding from the bar it is necessary to provide some means which will restrain the uncurling motion, and in the past this has been accomplished by a wire member secured to the bar and gripping member. Such arrangement does not permit the curl to be wound tightly against the head of the person since in winding it is not possible to judge with great accuracy how many turns of the bar are required to form a curl and hence a fixed restraining member may be a fraction of a turn removed from the most desirable restraining position. Other devices have provided a hair pin like member inserted in a hollow bar but such device has certain disadvantages, particularly when used with a perforated hollow bar in that it is difficult to insert the device into the bar and the rough interior of the bar does not readily permit the placement of the wire member in the most desired restraining position.

In accordance with the present invention the above mentioned disadvantages are overcome by providing a curling bar having at the end thereof an extension portion adapted to receive a restraining member which is resiliently retained in the desired position so as to have adequate inherent rotation resisting action relative to the bar.

It therefore is an object of the present invention to provide an improved curling bar with a restraining or lock member which obviates certain disadvantages of the devices of the prior art.

Other and further objects of the invention subsequently will become apparent from the following description taken in conjunction with the accompanying drawing in which

Figure 1 is a perspective view of a hair curler in operating position with a curl formed thereabout;

Figure 2 is an end view of the curl shown in Figure 1;

Figure 3 is one embodiment of the present invention;

Figures 4 and 5 are detailed views of a portion

2

of the device shown in Figure 3 explanatory of the construction and operation thereof;

Figure 6 shows the construction used where the curling bar has a greater diameter than that shown in Figure 3; and

Figure 7 shows another form of the locking or restraining member.

Referring to the drawing a curler 10 is shown in Figure 1 having thereon a curl 12 held in position by a restraining or locking member 14. In winding the curl the curler is rotated in the direction of the arrows shown in Figure 1 and when the curl has been completed the locking member 14 is rotated in an opposite direction to that shown by the arrows in the figure.

The details of the curler 10 and the locking member 14 are illustrated in Figures 3, 4, and 5 from which it becomes apparent that the curler 10 is provided with a hollow perforated bar portion 16 which is pivotally connected at 18 to a gripping member 20. The gripping member 20 is biased toward the bar 16 by a suitable spring 22 mounted adjacent the handle portions of the curler. At the open end of the curler 10 there is mounted in the hollow bar 16 an extension member 24 which for most sizes of curlers preferably is of hollow construction. The locking member 14 is mounted on the outer extremity of the extension member 24 by a member 26 comprising a resilient helical spring having a stop portion 28 adapted to engage the end of the extension 24. In order to provide the desired degree of resistance against rotation between the locking member 14 and the curler 10 at least one of the convolutions 30 of the helical spring 26 is offset slightly so that its center does not coincide with the axis of the remainder of the convolutions. Figure 4 illustrates how the outer extremity of the reduced diameter extension portion 24 is inserted into the helical spring portion 26 where it is about to engage the slightly displaced convolution 30. In Figure 5 it will be seen that the convolution 30 is in substantial alignment with the remaining convolutions of the helical portion 26.

Thus the convolution 30 produces a certain resilient bias which resists relative rotation between the locking member 14 and the curler 10.

In the use of the curlers of the type shown it frequently is desirable to use several sizes of curlers of different diameter. To facilitate hair curling where different diameter curlers are used it is possible to provide an arrangement such as shown in Figure 6 wherein the curler 10a is of larger diameter than the curler 10. In that case an extension member 24a is inserted within the

curler 10a so that the reduced end portion 25 thereof extends beyond the end of the curling bar 16a. The diameter of the extension portion 25 is the same diameter as the extension portion 24 of Figure 3 so that the same size locking member 14 may be used interchangeably with different size curlers.

In Figure 7 there is shown a curler 10 having an extension 24 embodying the same general structure as that shown in Figure 3. The locking member 30 has a helical spring gripping portion 32 one convolution of which may be displaced in the manner of the convolution 30 of the previous embodiment, and the locking member terminates in a handle portion 34. The handle portion 34 will facilitate the rotation of the locking member 30 when the curling operation takes place as was explained in connection with Figure 1.

While for the purpose of illustration and description, certain specific embodiments of the present invention have been shown, it is to be understood that the invention is not to be limited thereby since obviously such variations may be made as are commensurate with the scope of the appended claims.

The present invention is hereby claimed as follows:

1. A hair curler comprising a hollow bar on which a strand of hair may be wound, said bar being provided with an extension and a removable rotatable locking member adapted to maintain the strand in wound condition, said locking member comprising an exterior arm portion spaced from the surface of said bar to overlie the curl and a portion resiliently mounted on the exterior of an extension of said bar so as to have inherent rotation resisting relation therewith.

2. A hair curler comprising a hollow bar on which a strand of hair is to be wound, an extension for said bar carried thereby a demountable locking member adapted to maintain the strand in wound condition comprising an arm portion spaced from the surface of said bar to overlie the curl and a resilient coil spring portion adjustably mounted on the exterior of an extension of said bar so as to have inherent rotation resisting relation therewith.

3. A hair curler comprising a hollow bar on which a strand of hair may be wound, an extension member having a portion thereof rigidly mounted within said hollow bar and extending beyond the end of said bar, and a lock member rotatably mounted on said extension member so as to be moved to adjusted position to maintain the strand in wound condition, said lock member having a supporting portion in inherent resilient rotation resisting engagement with said extension member and an arm portion adapted to overlie the wound strand of hair.

4. A hair curler comprising a hollow bar on which a strand of hair may be wound, gripping means for securing end of said strand to the bar, an extension member having a portion thereof

rigidly mounted within said hollow bar and having a portion extending beyond the end of said bar, and a lock member rotatably carried by said extension member and having an arm spaced from the surface of said bar to overlie the curl and a resilient portion in engagement with said extension member to resist rotation of said arm relative to said bar, said lock member being adapted to be moved to an adjusted position to maintain the strand in wound condition.

5. A hair curler comprising a hollow bar on which a strand of hair may be wound, gripping means for securing end of said strand to the bar, an extension member having a portion thereof rigidly mounted within said hollow bar and having a portion extending beyond the end of said bar, and an adjustably positioned lock member rotatably carried on said extension member by a helically wound generally cylindrical shaped spring portion having at least a portion of one convolution thereof off center so that the center thereof is not coincident with the center of the remainder of the member.

25 6. A hair curler comprising a hollow bar on which a strand of hair may be wound, an extension member positioned at the end of said bar, said extension member being of lesser diameter than said bar, and a lock member to maintain the strand in wound condition, said lock member being carried on said extension member by a helically wound generally cylindrical shaped spring portion having at least a portion of one convolution thereof off-center so that the center thereof is not coincident with the center of the remainder of the member, said lock member being mounted by said spring for rotation to an adjusted position to maintain the strand in wound condition.

40 7. A hair curler comprising a hollow bar on which a strand of hair may be wound, said bar having an extension portion beyond the portion on which the strand is wound, and an adjustable locking member adapted to be moved to adjusted position relative to said bar to maintain the strand in wound condition, said locking member comprising an exterior arm portion spaced from the surface of said bar to overlie the curl and a resilient portion mounted on the exterior extension of said bar so as to have inherent rotation resisting relation therewith normally to retain said locking member in adjusted position.

45 8. A hair curler comprising a hollow bar on which a strand of hair is to be wound, said bar having an extension portion beyond the portion on which the strand is wound a demountable wire locking member adapted to maintain the strand in wound condition comprising a wire arm portion spaced from the surface of said bar to overlie the curl and a resilient coil spring portion mounted on the exterior of an extension of said bar so as to have inherent rotation resisting relation therewith.

RUDOLF KRASBERG.
